UNITED STATES PATENT OFFICE.

MEIER G. HILPERT, OF PITTSBURG, PENNSYLVANIA.

TOOL-RETAINER FOR AIR, ELECTRIC, OR MECHANICALLY-DRIVEN IMPLEMENTS.

959,530.

Specification of Letters Patent. Patented May 31, 1910.

Application filed November 30, 1904. Serial No. 234,923.

To all whom it may concern:

Be it known that I, MEIER G. HILPERT, a resident of Pittsburgh, in the county of Allegheny and State of Pennsylvania, have invented a new and useful Improvement in Tool - Retainers for Air, Electric, or Mechanically - Driven Implements; and I do hereby declare the following to be a full, clear, and exact description thereof.

10 My invention relates to fluid pressure implements, such as pneumatic riveting and chipping hammers, electrical hammers, and other implements having the tool loose and free to leave the barrel.

15 The invention relates to means for retaining or holding the tool against ejection from the barrel.

In the use of pneumatic riveting hammers and similar tools a difficulty is experienced by reason of the fact that if the air or other motive power is accidentally or purposely applied when the tool is not in contact with the work or other resistance, the tool, and frequently the piston 25 or plunger, will be forcibly ejected. When working on bridges or tall buildings these parts are liable to be lost, and even if again found the time expended in hunting for the same is a considerable loss. Furthermore, there is always the danger that the tool or plunger will strike the operator, or one of his co-workers, or on bridges or tall buildings will fall and strike a person below.

30 Many serious injuries have resulted from this cause. Many different devices have been used with a view of preventing the ejection of the tool and plunger when the air or other power is accidentally applied when the tool is out of contact with the work or other resistance. But none of these have proved satisfactory. In fact in the actual use of such tools at the present time there is no practical device which will prevent the ejection of the tool when out of 45 contact with the work or other resistance.

By reason of the loss of tools and plungers and the liability to personal injury from the ejection thereof, recourse has been made to complicated valve arrangements, or locking devices therefor, in order to prevent as far as possible the accidental admission of air to the hammer cylinder when the tool is not in contact with the work. Few of these, however, have proved satisfactory. At best 55 they complicate the hammer and over-tax

the hand of the operator, or provide extra valves, thus increasing the factor of clogging from dirt or otherwise.

My invention is designed to overcome the foregoing difficulties.

To this end it consists, generally stated, in providing an expansible spring holder or retainer for the tool, which is cheap to manufacture and easy of application to the hammer, and which will effectually prevent the tool (and of course the plunger) from being ejected even under full motive power operating the same when the tool is out of contact with the work, thereby preventing all losses of the tools and plungers, or injury to the operator, workmen, or others in the vicinity, and which will do away entirely with the complicated valve mechanism or locking devices which are sometimes resorted to to prevent the accidental admission of power to the implement.

The invention consists in a spring retainer and its manner of attachment to the barrel and tool as hereinafter more fully described and claimed.

In the accompanying drawings Figure 1 is a side view of a standard type of pneumatic riveting hammer showing my invention applied thereto; Fig. 2 is a longitudinal section through the end portion thereof; Fig. 3 is a cross section through the barrel taken just above the retaining lugs; Fig. 4 shows one of the springs extended and also in its unrestrained position; Fig. 5 shows the spring retainer in side and both end views; Fig. 6 is a perspective view of the outer end of the spring, showing a modification; Figs. 7 and 8 are side views of the end of the device showing modifications of the manner of attaching the springs to the barrel; Fig. 9 is a similar view showing still another modification; Fig. 10 is a side view of the barrel of the modification; Fig. 11 is an end view of the spring; Fig. 12 is a side view showing still another modification of the manner of attaching the retainer to the barrel; and Fig. 13 is a perspective view of the attaching means of this modification.

In the drawings my invention is shown applied to a pneumatic riveting hammer of a standard type, but it will be understood that it is applicable to all forms of fluid pressure implements, electrical implements, or even mechanically driven implements which have a barrel containing an actuating

plunger and a tool projecting loosely through the end of the barrel and actuated by the plunger.

The implement shown in the drawings 5 comprises a barrel 1 provided with the usual handle 2 and containing the actuating piston or plunger 3, and tool 4, the latter projecting through the outer end of the barrel with its inner end in position to be actuated by the piston. All of these parts are 10 or may be of the usual or any desired construction.

My invention does not necessitate any alteration whatsoever in the internal mechanism of the implement but is applied, 15 preferably externally, for the purpose of preventing the ejection of the tool when motive fluid is applied while the tool is not in contact with the work, or other resistance.

20 My retainer is an extensible spring retainer 6 which will be of coiled or helical form, and preferably slightly conical, as shown in the drawings, this retainer having one end attached to the barrel and the opposite site end provided with means for engaging the tool. Preferably the retainer will consist of a plurality of helical springs nested together, and preferably in the same cylindrical or conical plane, four such springs 7 25 being shown in the drawings, but obviously one or any greater number may be employed. These springs will be formed from any suitable spring material, those shown in the drawing being formed of wire essentially 30 square in cross section, but this obviously is a matter of choice, as they may be formed from round wire, or round wire flattened on two or more sides, or wire rectangular in cross section, or either rectangular or square 35 in cross section and having rounded corners, or any desirable cross section. The several springs forming the retainer will preferably be so made that when separate they will practically have one coil tight against the other, as shown in Fig. 4. As a consequence 40 when they are twisted together so as to form the nest the individual springs will be put under an initial tension, that is, they will be extended slightly from the position they 45 would take if unrestrained. The spring or 50 springs making up this retainer will be attached to the barrel and made to engage the tool in any suitable way. Several modifications for accomplishing these results are 55 shown in the drawings.

The tool 4 is provided with a shoulder or shoulders, preferably an annular enlargement or shoulder 9, and the outer end or 60 ends of the spring or springs will be provided with suitable means projecting inwardly and extending below the shoulder or shoulders of the tool. This may be done by attaching to the lower end of the spring or springs suitable projecting means, but preferably the end of the spring or springs will

be turned inwardly either by giving the same a single bend, as shown in Fig. 5, or a double bend as shown in Fig. 6, or by merely giving the lower end of the spring an inward trend as shown in Fig. 11. In all 70 cases there is at the lower end of the spring a portion 10 which projects radially inwardly toward the axis of the coil, and consequently will be in position to be engaged by the shoulder 9 on the tool. Preferably 75 the inwardly projecting portion or portions 10 will be located so that in the normal operation of the implement the shoulder on the tool will not contact therewith. When, however, the implement is operated with the tool 80 out of contact with the work or other resistance, the shoulder on the tool will strike against these inwardly projecting portions 10 and the tool will be held thereby against 85 ejection from the barrel.

90 The upper end or ends of the spring or springs may be attached to the barrel in many different ways. In Figs. 1 to 5 these springs are provided with hooked ends 12 which engage shoulders or lugs 13 secured to or integral with the barrel, preferably the latter. These shoulders may be conveniently formed by turning a rib from the excess diameter of the barrel and slotting the same longitudinally of the barrel, as at 14, thus 95 providing openings through which the hooked ends of the springs may be passed, and then by giving the same a slight turn relatively to the barrel the hooks 12 will engage the shoulders 13 to secure the springs 100 in place. In order to prevent the accidental rotation of the springs on the barrel and the disengagement of the hooks from the shoulders 13 said hooks are given a slight inward bend as indicated in Fig. 5, and these engage 105 depressions 15 formed in the side of the barrel, such as by merely flattening the same. If desired a more decided depression and a more decided inward bend or hook may be formed on the spring. 110

In Fig. 8 is shown a modification wherein the spring is provided with an eye 16 through which passes a screw or pin 17 for attachment to the barrel.

In Fig. 7 is shown a modification wherein 115 the hook at the upper end of the spring is bent in the reverse direction, as at 18, and likewise engages a shoulder or lug formed on the barrel.

In Figs. 9, 10 and 11 the barrel is provided with seats or depressions 19, and the upper ends of the springs are merely given an inward trend, as at 20, and slipped into these sockets when given a partial turn. 120 The bottoms of the recesses 19 are practically flat, and the inner faces of the end portions 20 of the springs are practically straight, so that thereby the spring is locked against accidental rotation on the barrel. If desired, the sockets may be mere holes 130

and the ends of the springs turned inwardly 5 radially to form hooks which take into the sockets.

In Figs. 12 and 13 the springs are shown riveted or otherwise suitably secured to a clip 21 provided with hooks 22 for engaging the lugs on the barrel. This clip may be formed from a plate stamped to shape and bent into circular form. Any other intermediate fastening may be used to secure the springs to the barrel.

Various other manners of connecting the springs to the barrel and of causing said springs to engage the tool will suggest themselves to those skilled in the art. The different means shown in the drawings are intended as illustrative largely, and not to be exhaustive of the different ways in which these attachments may be made. The end of the barrel will be slightly tapered as shown in Fig. 2, so that when the springs of the retainer extend as they will under the impact to the tool, they will not bind on the barrel as would be the case if the barrel and springs were cylindrical and the springs fitted tightly on the cylindrical surface.

The spring or springs forming my retainer can be cheaply made by merely coiling them to the desired shape and bending the ends in any of the manners described, after which the springs are tempered. I prefer to use a plurality of such springs nested together as shown, but wish it understood that a single spring comes within the scope of my invention. When several springs are used they will preferably be twisted one in the other so as to form the cylindrical or conical nest and place the individual springs under an initial tension the better to resist the pull of the tool. These nested springs preferably will all be of the same shape, thus giving a smooth exterior finish, though if desired one spring may be placed inside another, and the upper and lower ends of the springs will be practically in the same transverse plane. The springs when thus nested or assembled can be conveniently handled or shipped without liability of disengagement. In order to put them in place the tool will first be inserted in the barrel and then the retainer will be passed over the same and up over the end of the barrel until the hooked ends pass the lugs on the latter, and then by giving the barrel and retainer a partial rotation the retainer will be locked to the barrel. The lugs at the lower ends of the springs will not be in contact with the shoulder on the tool while in normal operation, so that no strain whatsoever is placed upon the springs nor do the latter interfere with the proper working of the tool. Should, however, the motive power be applied when the tool is not in contact with the work or other resistance the latter will be forcibly driven out,

the shoulder thereof will engage the lugs on the lower ends of the springs and will pull out or extend said springs, and the latter will at once return the tool to its normal position, the latter gradually stopping the tool, thus doing away with the shock which would occur if a rigid retainer were employed. In this way the tool is absolutely held against ejection and without imposing any severe strain upon either the springs or barrel of the implement.

My device can be cheaply manufactured, and is very easy of attachment to fluid pressure, electrical and other implements, and without the necessity of at all interfering with the usual mechanism or mode of operation of such implements. The tools are absolutely prevented from ejection, thus avoiding the expense due to the loss of the tools and plungers, or the time expended in hunting for the same, and also preventing injury to the operator, workmen, or others in the vicinity.

Many modifications can be made in the number and shape of the springs, the nesting thereof, their location, and the manner of engaging the tool and attachment to the barrel.

What I claim is:

1. In an implement of the character specified, the combination with a barrel containing a plunger and having an unobstructed opening through which the tool may be withdrawn, of a tool projecting through said opening, and a coiled spring encircling the barrel and held at one end by the barrel and having the other end provided with tool engaging means.

2. In an implement of the character specified, the combination with a barrel containing a plunger and having an unobstructed opening through which the tool may be withdrawn, of a tool projecting through said opening, and a helical tension spring surrounding the axis of the barrel and having the inner end held by the barrel and the outer end provided with tool engaging means and being extensible along the axis of the barrel when the tool is driven outward by the plunger.

3. In an implement of the character specified, the combination with a barrel containing a plunger and having an unobstructed opening through which the tool may be withdrawn, of a tool projecting through said opening, and a plurality of helical springs surrounding the axis of the barrel and having one end held by the barrel and the other end provided with tool engaging means.

4. In an implement of the character specified, the combination with a barrel containing a plunger and having an unobstructed opening through which the tool may be withdrawn, of a tool projecting through

said opening, and a plurality of helical springs of the same diameter nested together with their coils in a common curved surface and provided on one end with means for engaging the barrel and on the opposite end with tool engaging means.

5. In an implement of the character specified, the combination with a barrel containing a plunger and having an unobstructed 10 opening through which the tool may be withdrawn and provided with a conical end, of a tool projecting through said opening, and a plurality of conical coiled springs surrounding said barrel and held at their inner 15 ends by the barrel and having their outer ends provided with tool engaging means.

6. In an implement of the character specified, the combination with a barrel having a plunger and an unobstructed opening 20 through which the tool may be withdrawn, of a tool projecting through said opening, and a plurality of helical springs nested together and having their ends in substantially the same transverse plane and held at their 25 inner ends by the barrel and having their outer ends provided with tool engaging means.

7. In an implement of the character specified, the combination with a barrel containing 30 a plunger and having an unobstructed opening through which the tool may be withdrawn, of a tool projecting through said opening, and a plurality of coiled springs surrounding the axis of said barrel 35 and having their inner ends engaging shoulders or lugs on the barrel and their outer ends provided with tool engaging means.

8. In an implement of the character specified, the combination with a barrel containing 40 a plunger and having an unobstructed opening through which the tool may be withdrawn, of a tool projecting through said opening, and a coiled or helical spring surrounding the axis of said barrel and having 45 a hooked end engaging a shoulder or lug on the barrel and having its opposite end provided with tool engaging means.

9. In an implement of the character specified, the combination with a barrel containing 50 a plunger and having an unobstructed opening through which the tool may be withdrawn, of a tool projecting through said opening, and a plurality of coiled or helical springs nested together and provided 55 at one end with hooks engaging shoulders or lugs on the barrel and having their opposite ends provided with tool engaging means.

10. In an implement of the character specified, the combination with a barrel and its 60 plunger, of a tool projecting from the barrel, and a coiled spring surrounding the axis of the barrel and tool and having one end provided with tool engaging means and having 65 its opposite end engaging a shoulder or lug on the barrel and bearing against said

barrel with a friction grip, thereby to prevent rotation on the barrel.

11. In an implement of the character specified, the combination of a barrel and its plunger, of a tool projecting from the barrel, and a coiled or helical spring surrounding the axis of said barrel and tool and having one end provided with tool engaging means and having its opposite end bent to engage a shoulder or lug on the barrel and bent inwardly and engaging a depression formed in said barrel.

12. In an implement of the character specified, the combination with a barrel and its plunger, of a tool projecting from the barrel, and two or more coiled or helical springs nested together and having one of their ends provided with tool engaging means and having their opposite ends engaging lugs or shoulders on the barrel and bearing against 85 said barrel with a friction grip, whereby to prevent rotation on the barrel.

13. In an implement of the character specified, the combination with a barrel and its plunger, of a tool projecting from the barrel, a plurality of helical springs nested together and having one of their ends provided with tool engaging means and having their opposite ends provided with hooks, and shoulders on the barrel with grooves therebetween, whereby the hooked ends of the 95 springs may be passed through said grooves and made to engage the shoulders by a part turn.

14. In an implement of the character specified, the combination with a barrel and its plunger, of a tool projecting from the barrel, a plurality of shoulders on said barrel, a plurality of helical springs of the same 100 diameter nested together with their coils lying in a common curved surface and provided on one of their outer ends with tool 105 engaging means and having their inner ends provided with bent portions for engaging the shoulders on the barrel.

15. In an implement of the character specified, the combination with a barrel and its plunger, the end of the barrel being tapered, of a tool projecting from the barrel, and a coiled or helical spring surrounding the tapered end of said barrel and tool and held at one end by the barrel and having its opposite end provided with means for engaging the tool.

16. In an implement of the character specified, the combination with a barrel and its plunger, of a tool projecting from the barrel and so arranged as to be free to leave the barrel, a shoulder formed on said tool, and a coiled or helical spring having one end held by the barrel and its opposite end provided with means projecting within the path 125 of the shoulder on the tool.

17. In an implement of the character specified, the combination with a barrel and its 130

plunger, of a tool projecting from the barrel and provided with a shoulder, of a plurality of extensible springs having one of their ends held by the barrel and their opposite 5 ends provided with means projecting into the path of the shoulder on the tool.

18. In an implement of the character specified, the combination with a barrel and its plunger, of a tool projecting from the 10 barrel and provided with a shoulder, and a plurality of coiled or helical springs surrounding the axis of said barrel and tool and having one of their ends held by the barrel and having their opposite ends provided with means projecting into the path of the 15 shoulder on the tool.

19. In an implement of the character specified, the combination with a barrel and its plunger, of a tool projecting from the 20 barrel and provided with a shoulder, of a plurality of coiled or helical springs of substantially the same diameter nested together and surrounding the axis of said barrel and tool and having one of their ends held by 25 the barrel and their opposite ends bent and projecting into the path of the shoulder of the tool.

20. In an implement of the character specified, the combination with a barrel and 30 its plunger, of a tool projecting from the barrel and provided with a shoulder, of a plurality of coiled or helical springs nested together, said springs at one end being in substantially the same transverse plane and 35 provided with means lying in the path of the shoulder of the tool and having their opposite ends held by the barrel.

21. In an implement of the character specified, the combination with a barrel containing 40 a plunger and having an unobstructed opening through which the tool may be withdrawn, of a tool projecting through said opening and provided with a shoulder, said barrel being also provided with a shoulder, and a plurality of coiled or 45 helical springs surrounding the axis of the barrel and having their inner ends provided with means for engaging the shoulder of the barrel and their outer ends provided 50 with means projecting into the path of the shoulder on the tool.

22. In an implement of the character specified, the combination with a barrel con-

taining a plunger and having an unobstructed opening through which the tool 55 may be withdrawn, of a tool projecting through said opening and provided with a shoulder and a plurality of coiled or helical springs of substantially the same diameter nested together in the same curved surface 60 and beginning and ending in the same transverse planes and having one of their ends provided with means engaging the barrel and their opposite ends provided with means projecting into the path of the 65 shoulder on the tool.

23. In an implement of the character specified, the combination with a barrel and its plunger, of a tool projecting from the barrel and provided with an annular shoulder, a plurality of coiled or helical springs surrounding the axis of said barrel and tool and having one of their ends held by the barrel and their opposite ends provided with means projecting into the path of the 70 shoulder on the tool but being out of contact therewith during normal operation of the tool.

24. A tool retainer comprising a plurality of helical springs of substantially the same 80 diameter and nested together with their coils lying within a common curved surface and provided on their one end with means for engaging a tool and on their opposite ends with means for attachment to a barrel. 85

25. A tool retainer comprising a plurality of coiled or helical springs nested together and having their one ends provided with inwardly projecting means for engaging a 90 tool and having their opposite ends provided with means for attachment to a barrel.

26. A tool retainer comprising a plurality of coiled or helical springs nested together in the same curved surface and having their 95 outer ends lying in the same transverse plane and provided with inwardly projecting means and being provided at their opposite ends with means for attachment to a barrel. 100

In testimony whereof, I the said MEIER G. HILPERT have hereunto set my hand.

MEIER G. HILPERT.
